UNITED STATES PATENT OFFICE.

FRANK M. LEE, OF CHICAGO, ILLINOIS, ASSIGNOR TO SULLIVAN MACHINERY COMPANY, A CORPORATION OF MASSACHUSETTS.

CHANNELER MECHANISM.

Application filed April 27, 1922. Serial No. 556,967.

My invention relates to channeler mechanisms and more particularly to channeler gangs.

An object of my invention is to provide an improved channeler gang. Another object of my invention is to provide an improved channeler gang which will work equally well irrespective of the direction of movement of the gang during cutting, and 10 which will prevent the excessive wear now very common with channeler gangs which results in a reduction in width of the cutting edges and so a rapid loss of efficiency as the steels wear, and which also results in a 15 "stunning" or shattering of the material at the sides of the channel due to the dullness of the steels. This last is of great importance as the shattering may injure the stone for several inches inside its surface. 20 In the accompanying drawings I have shown for purposes of illustration one form which my invention may assume in practice.

In these drawings,—

Fig. 1 is a side elevation of the lower extremity of a channeler gang.

Fig. 2 is a bottom view of this gang.

Fig. 3 is a section on the line 3—3 of Fig. 1.

In the illustrative form of my invention 30 I have shown the same incorporated in a channeler gang made up of five steels, three of these steels being of the cutting type and two of the leveling type. It will be noted that a central steel 1 is provided with a 35 chisel-like transversely extending cutting edge 2, this edge being of a width equal to the desired width of the channel to be cut and of considerably greater width than the thickness of the gang itself. On opposite 40 sides of the steel 1 are steels provided with leveling edges, these steels being designated 3 and terminating in X-shaped leveling edges 4, these leveling edges likewise extending, although diagonally, entirely across 45 the desired width of the channel to be cut and terminating in reaming edges 5 lying in the planes of the sides of the cut. The ends of the wings supporting the edges 4 will do a large portion of the reaming necessary 50 to maintain the full width of the channel. It will be noted that the central portions of the edges 4 are cut away or flattened as indicated at 6, this reducing the shock and the reduction in penetration that 55 would result from the intersection of the

edges 4. It will be observed that the leveling edges 4 are set back a material distance from the bottom of the cutting edge 2. Outside of the steels 3 are additional steels 7 whose edges terminate in cutting edges 8 60 similar to the cutting edge 2 and like that edge extend completely across the groove, but set back above the edge 2 a material distance although these edges are not set back quite so far as the leveling edges 4. The 65 degree of advance of the edges 8 under the edges 4, however, is but slight. It will be understood that the ends of the edges of the steels 1 and 7 lie in surfaces in which reaming edges at the sides of the steel are also 70 found, and these reaming edges are saved by the similar edges on the steels 3.

From the foregoing description the mode of operation of my improved channeler gang will be clearly apparent. Assume that 75 the gang is being reciprocated and is making a cut from left to right. The cutting edge 8 of the right hand steel 7 will then cut a series of closely spaced notches penetrating the stone for a material distance, 80 say, depending upon the hardness of the stone, $\frac{1}{16}$ of an inch; the leveling edges 4 next behind the edge 8 will then smooth down the parallel transverse ridges in the bottom of the cut, and next the edge 2 passes 85 over the cut and leveled surface and form a second series of notches. When the channeler reaches the opposite end of its cut and starts back the other steel 7 will work along during the initial cutting, although the cutting down by this steel will not be so great as will be the case were the edge 2 not present, for the edge 2 having made a material 90 cut will not leave so much work for the edge 8 to accomplish. The left hand pair 95 of X-like leveling edges 4 smooth down the ridges left after the edge 8 has passed and the edge 2 will then again cut a deeper series of notches in the leveled stone.

This channeler gang has given excellent 100 satisfaction in practice and by reason of the multiplicity of leveling edges 4 preserves the cutting edges and maintains the full width of the channel, the tendency to round off of the cutting edges 2 and 8 being markedly reduced since the ends of the wings which support the edges 4 do a large part 105 of the reaming necessary. Further the presence of the cutting edge 2 considerably relieves the edges 8 of the work of maintain- 110

ing a full width cut clear to the bottom, and accordingly all the steels of the gang cooperate in producing an improved gang in which the wearing away of the corners of the cutting edges (resulting either in a resultant narrowing of the gage of the channel or the need for changing steels in the gangs at frequent intervals) is avoided.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A channeler gang comprising a central cutting edge, cutting edges arranged on each side of said cutting edge, and a plurality of X-shaped intermediate leveling edges between said central cutting edge and each of said other cutting edges, said side edge cutting edges and said leveling edges being set back from said central cutting edge.

2. A channeler gang comprising a central cutting edge, cutting edges arranged on each side thereof and set back from the horizontal plane of said central cutting edge, and a plurality of intermediate leveling edges between said central cutting edge and each of said other cutting edges, said leveling edges being disposed outside of the zone between the horizontal planes in which said cutting edges lie.

3. A channeler gang comprising a central cutting edge, cutting edges arranged on each side of said cutting edge and set back from the horizontal plane of said central cutting edge, and a plurality of intermediate X-shaped leveling edges between said central cutting edge and each of said other cutting edges, said leveling edges terminating in reaming edges.

4. A channeler gang comprising a central cutting edge, cutting edges arranged on each side of said cutting edge and set back from the horizontal plane of said central cutting edge, and a plurality of intermediate X-shaped leveling edges between said central cutting edge and each of said other cutting edges, said leveling edges terminating in reaming edges that lie in planes disposed laterally to the shank portion of said gang.

5. A channeler gang comprising a central cutting edge, cutting edges arranged on each side of said cutting edge and set back from the horizontal plane of said central cutting

edge, and intermediate X-shaped leveling edges between said central cutting edge and each of said other cutting edges.

6. A channeler gang comprising a plurality of cutting edges and a greater number of X-shaped leveling edges. 65

7. A channeler gang comprising a leading cutting edge, a plurality of following X-shaped leveling edges, and a second cutting edge disposed outside of the horizontal plane in which the other cutting edge lies. 70

8. A channeler gang comprising a leading cutting edge, a plurality of following X-shaped leveling edges terminating in reaming edges, and a second cutting edge. 75

9. A channeler gang comprising a steel terminating in X-shaped leveling edges, the wings supporting said edges terminating in reaming edges. 80

10. A channeler gang comprising a steel having intersecting terminal diagonal edges ending in reaming edges lying in the planes of the sides of the cut. 85

11. A channeler gang comprising a steel having intersecting terminal diagonal edges ending in reaming edges lying in the planes of the sides of the cut and laterally of the steel shank. 90

12. A channeler gang comprising a central steel having a cutting edge projecting further than the edge of any other steel, and symmetrically arranged cutting and X-shaped leveling edges arranged at opposite sides of said central edge. 95

13. A channeler gang comprising a steel having acutely angled crossed edges. 100

14. A channeler gang comprising a plurality of transverse cutting edges and spaced intermediate crossed edges. 105

15. A channeler gang comprising a central cutting edge, cutting edges at each side of said cutting edge, and spaced intermediate crossed leveling edges disposed between said cutting edges. 110

16. A channeler gang comprising a plurality of cutting edges, spaced crossed leveling edges disposed between said cutting edges, and reaming edges formed adjacent said cutting edges. 115

17. A channeler gang comprising a plurality of steels having straight and spaced crossed cutting edges disposed in different horizontal planes. 120

18. A channeler gang comprising a cutting edge, an X-shaped leveling edge set back from the horizontal plane of said cutting edge, and a cutting edge disposed below the horizontal plane of said first mentioned cutting edge.

In testimony whereof I affix my signature.
FRANK M. LEE.
